J. PETERS.

Sausage Cutter.

No. 17,980.

Patented Aug. 11, 1857.

UNITED STATES PATENT OFFICE.

JACOB PETERS, OF HUMMELSTOWN, PENNSYLVANIA.

SAUSAGE-CUTTER.

Specification of Letters Patent No. 17,980, dated August 11, 1857.

To all whom it may concern:

Be it known that I, JACOB PETERS, of Hummelstown, in the county of Dauphin and State of Pennsylvania, have invented 5 certain new and useful Improvements in Sausage-Cutters; and I do hereby declare that the following is a full, clear, and exact description of the same, reference being had to the accompanying drawings and to the 10 letters of reference marked thereon.

The nature of my invention consists in an arrangement of sashes containing knives—the sashes working all in different directions thereby giving the knives a draw cut. 15 In order that those skilled in the art may use and construct my machine I will proceed to describe its operation and construction.

In the accompanying drawings which 20 make a part of this specification, Figure 1 is a side elevation. Fig. 2 is a front view showing the knives. Fig. 3 is a front view of the sash (a) and (b) seen in Fig. 1 showing their respective positions and the 25 interlapping of their knives.

In Fig. 1 A is a box into which the meat is put. C is a beam on which the box A rests. B are the legs of the machine. D is a wheel with cogs and driven by wheel E 30 which also has cogs on it. t is a pinion on shaft t'. This pinion works in a rack seen on the follower f. f is a follower with head fitting in the box A which serves to force the meat up against the knives. Y, is a 35 hopper through which the meat enters the box A. r, is a crank for setting the machine in motion. q, is a crank on the shaft of wheel E. p and j are levers, p being attached to crank q, and j attached to rod i, 40 serving to operate the knife d to which one end of rod (i) is attached. n is a standard having an arm to which is attached the vibrating lever k, which works on a pivot on this arm. F is a rod connecting lever k and 45 crank q. l, is a rod connecting lever k to sash a, and m, is a rod connecting lever k to sash b. (a) is a sash having knives in it, which knives work between and in a contrary direction to the knives in sash (b).

50 c is a sash having knives in it which works transversely of the machine and is operated by a lever (u) seen in Fig. 2. (d) is a double edged knife which works in front of the sash (c) and serves to cut the meat off 55 in both ways as it is forced through. (g) is a guide rod, for the knife (d) and h, is

a guide block through which the rod (g) passes. (O) is a standard and serves to support lever (j) which works on pivot near its upper extremity.

60

In Fig. 2, (a) is a sash containing knives and works vertically. (c) is a sash also containing knives and works transversely. (d) is a knife, double edged, which works in front of sash (c) for cutting off the meat 65 (u) is a lever attached by a loop to sash a having (v) for a fulcrum and serves to operate sash (c). (g) is a guide bar for the knife (d). (i) is a rod for operating knife (d). w, w, w, are knives in sash a, and 70 w' w' w' are knives in the transverse sash (c).

In the operation of this invention the meat is introduced through the aperture (y,) after the follower has been brought back to 75 the rear of the machine and the hopper. When the box is filled with meat the crank (r) may be turned and the machine is set in motion; the follower f being driven by pinion t forces the meat up to the knives and 80 against them. The knives all have a saw cut. As the sash (a) moves up while the sash (b) is moving down, and as the knives in these two sashes work between each other they have a tendency to prevent the meat 85 moving either up or down, consequently it remains stationary while the knives saw through it; sash (c) moving in a different direction cuts the meat in another way, and after it passes or as it passes it is sheared 90 off by both the up and down motion of knife (d).

It will be seen that the contrary motion of the sashes a, and b, are produced by their being attached to lever, k, on different sides 95 of its center where it is pivoted to the arm of standard (n). The lever k has a vibrating motion like the pendulum of a clock; the sash (a) serves to communicate motion to sash c, by means of the lever u, seen in 100 Fig. 2.

I do not propose to confine myself to the precise proportions to be found in my machine. The follower may be geared much lower so as not to crowd the meat up too 105 fast, and the stroke of the knife (d) may be made more frequent, so that the meat may be shaved off or cut into small bits as may be desired.

I can by this machine make the meat as 110 fine as desired by putting the knives in the sashes closer together and giving more mo-

tion to knife (d). The meat will be forced up regularly and certainly by the follower and this together with the draw cut of the knives will effectually prevent any choking 5 or clogging of the machine.

One of the chief advantages of this machine is the rapidity and accuracy with which it may be made to operate, preparing any given amount of meat in a better manner 10 and in shorter time than any machine now in use.

I claim—

The employment of the vertical sash (a, and b,) the one arranged within the other, 15 as seen in Fig. 3, their knives interlapping and operating in different directions for the

purpose of sawing and more effectually preparing the meat, as herein fully set forth and described, it being understood that I do not claim the main features of the machine, 20 as it is not in that respect new, nor yet the device merely of giving a sawing motion to the fixed knives of meat cutters, this also being not new, but only the arrangement here specified of two sets of knives working 25 into each other with motions in opposite directions.

JACOB PETERS
